CHESTERFIELD BED

Filed Dec. 23, 1946

UNITED STATES PATENT OFFICE

2,607,049

CHESTERFIELD BED

Edward George Hirst, York Mills, Toronto,
Canada

Application December 23, 1946, Serial No. 717,893

5 Claims. (Cl. 5—43)

1

This invention relates to improvements in a type of furniture in which a bed is arranged within a chesterfield structure and the principal object of the invention is to provide an article of furniture which will have the appearance of a chesterfield and can be used as such but which may be instantly converted into a comfortable bed.

The principal feature of the invention consists in the novel construction of a chesterfield frame having a shallow cabinet forming the back with rigid arms extending from the open front between which a bed frame is pivotally supported on arms pivotally mounted in the base of the cabinet, a sloping back being secured to the underside of the bed frame and a seat and front panel for the chesterfield being foldably connected to said back to fold under the bed when the bed frame is swung outwardly from the cabinet.

In the accompanying drawings Figure 1 is a perspective view of my improved device shown with the bed enclosed and the chesterfield structure in position for use, the upholstery being indicated by dotted lines.

Figure 2 is a vertical cross sectional view, partly broken away, showing the structure as illustrated in Figure 1.

Figure 3 is a vertical cross sectional view showing the bed in the extended position and the chesterfield seat folded thereunder.

Figure 4 is a vertical sectional view through one of the chesterfield arms and the adjacent end of the bed frame when in the extended position taken on the line 4—4 of Figure 3.

Figure 5 is a vertical sectional view taken on the line 5—5 of Figure 3.

In present-day living conditions where apartment space is extremely limited it is desirable that utility furniture be provided which will occupy the minimum of space but will afford the maximum of comfort for seating and sleeping accommodation while presenting an acceptable appearance.

In the device herein illustrated as shown in the drawings I have constructed a shallow cabinet 1 with suitably ornate top 2 and end panels 3 and having an open front.

Extending from the open front of the cabinet at each end is a panel 4 preferably shaped to form the end arms of a chesterfield. These arm panels may be provided with broad arms or may be upholstered in a desirable manner.

Secured to the inner faces of each of the arm panels 4 within the cabinet are plates 5, prefer-

2

ably of metal which have formed therein an upright guideway 6 which is formed with an upwardly and forwardly curving terminal portion 7.

5 A lug 8, preferably formed on the inward side of each plate 5 adjacent to the bottom and arranged forward of the guideway 6, forms a pivot support for a flat bar 9 which extends upwardly and is adapted to swing forwardly and downwardly from the upright position illustrated in Figure 2.

10 End panels 10 rigidly connected by longitudinal bars 11 and 12 to form a bed frame are each provided with a bracket 13 arranged substantially centrally of their length and these brackets are provided with pivot studs 14 which pivotally connect same to the bars 9 at a point adjacent to but spaced from the free outer end.

15 A bed spring 15 of suitable construction is mounted in the bed frame between the end panels 10 and the side bars 11 and 12.

20 Roller pins 16 are suitably mounted on the outward sides of the end panels 10 of the bed frame and these rollers extend into and engage the 25 edge walls of the guideways 6.

When the bed frame is in the vertical position housed within the cabinet 1 as shown in Figure 2 the roller pins 16 rest in the bottom of the guideways 6 and the bars 9 will be parallel therewith.

30 When the top edge of the bed frame is pulled outwardly the bars 9 swing outwardly upon their pivot supports and the frame pivoting on the bracket pivots 14 swings to a horizontal position, the lower and inward side being guided by the 35 rollers 16 engaging the guideways 6.

The guideways limit the upward movement of the rollers and the pivot bars 9 form forwardly angled struts supporting the frame while the rollers move into the horizontal terminal ends of 40 the guideways, thus supporting the frame rigidly in the extended position.

A vertical block 17 forming part of each of the end panels 4 and extending inwardly therefrom forms a further rigid support for the outward edge of the bed frame when extended.

45 A head panel 18 is suitably hinged to the upper edge of each of the end panels 10 of the bed frame and these are adapted to fold inwardly over the mattress and bed clothes placed upon the bed spring so as to hold same in place when the bed is moved to the vertical position.

An eye 19 is secured to the inward side of each panel 18 near the hinged edge and a link 20 connected to each of said eyes is pivotally connected to the outer end of each of the bars 9 so

that as the bed is swung outwardly the links lift the panels 18 to a vertical position and form head and foot boards for the bed frame.

Thin plates 21 of wood or metal are secured to and extend outwardly from the outward sides of the end members of the bed frame or they may form a part thereof. These plates support a longitudinal panel 22 arranged in a sloping position which when the bed is in the vertical position forms the back of the chesterfield. This panel may be suitably upholstered on its outer face as indicated by dotted lines.

At the bottom or inward edge of the chesterfield back panel 22 there is arranged an angularly disposed strip 23 to support the bottom edge 15 of the back upholstery.

Secured by suitable hinges to the forward edge of the strip 23 is a seat board 24, the top of which may be upholstered, or upholstered cushions may be placed thereon.

A front panel 25 is hinged in a suitable manner to the underside of the seat board 24 at its forward edge, and a pair of links 26, arranged one at each end are pivoted to the front panel slightly below the hinge. The links 26 are pivotally secured at their inner ends to blocks 27 secured beneath the strip 23 and operate to swing the front panel 25 to and from a vertical position as the seat board swings on its hinges.

In swinging the bed outwardly as it tilts on its centre pivots 16 on the bars 9 the links 26 pull inwardly and swing the front panel 25 inward and the seat board is swung on its hinges to close in toward the back 22. The back being rigid with the bed frame is carried under same as it is swung outward when the bed is to be used and when the bed is swung upwardly to be housed within the cabinet 1 the seat 24 swings downwardly and the front panel swings outwardly all with a single co-ordinated movement.

When the bed is closed, there will be an opening between the top 2 of the cabinet and the panel 22 of the chesterfield back, on account of the width of the bed and this is closed by a removable panel 28, which, when the bed is open, may be supported under the top, being held in place by suitable guide pins or strips 29.

A piece of furniture such as described may be finished to suit other furnishings and provides a useful seat and a serviceable bed which may be converted to either with a very simple unitary operation.

What I claim as my invention is:

1. A foldaway chesterfield bed construction, comprising, in combination, with a casing and a rectangular bed frame pivotally swingable about a longitudinal axis intermediate the width of said frame into and out of said casing, a chesterfield back panel rigidly secured to the underside of said bed frame so as to extend from adjacent one longitudinal edge across beneath said frame in spaced apart relationship therewith, an extension projecting from the lower marginal edge of said back panel, a seat portion having one edge hinged to said back panel above said extension, a front panel hinged to the other edge of said seat por-

tion, and connecting links pivotally attached to said back panel extension and to said hinged front panel adjacent the upper margin thereof to form a pivotal linkage therebetween, whereby the outward movement of said bed frame about said longitudinal axis is adapted to cause an inward movement of said back panel extension with respect to said casing and said inward movement is transmitted through said pivotal connecting links to cause a corresponding inward movement of said front panel with respect to said seat portion, causing said back panel, hinged seat and front panel to fold into juxtaposed collapsed position beneath said bed frame.

2. A foldaway chesterfield bed construction according to claim 1 in which the bed frame includes a pair of boards one at each end extending beneath said frame, a supporting plate attached to each end board, said back panel being attached to said end plates.

3. A foldaway chesterfield bed construction according to claim 1 wherein said back panel extension comprises a block attached to and extending downwardly from the back panel at each end of the back panel, each of said links being pivoted at one end to one of said blocks and at the other end to said front panel adjacent the hinged connection with said seat portion.

4. A foldaway chesterfield bed construction according to claim 1 in which the frame includes a pair of boards one at each end extending beneath said frame, a supporting plate attached to each end board, said back panel being attached to said end plates and said back panel extension comprises a block attached to and extending downwardly from the back at each end of the panel, each of said connecting links being pivoted at one end to one of said blocks and at the other end to said front panel adjacent the hinged connection with said seat portion.

5. A foldaway chesterfield bed construction according to claim 1, in which the back panel when in one position within said casing stops short of the top of the casing, and a removable panel between the top of the back panel and the top of the casing to close the front of said casing, the panel being removable to allow outward pivotal movement of the top longitudinal side of the bed frame.
